Patented Feb. 8, 1972

222,957

FLUID DELIVERY APPARATUS

Stephens N. Sato, San Diego, Calif., assignor to
Ivac Corporation, San Diego, Calif.

Continuation-in-part of design application Ser. No. 20,774,
Jan. 6, 1970. This application Sept. 16, 1970, Ser.
No. 25,030

Term of patent 14 years

Int. Cl. D24—02

U.S. Cl. D83—1

Fig. 1

Fig. 2

Fig. 3

Fig. 4

Fig. 5

FIG. 1 is a front perspective view of a fluid delivery apparatus embodying my new design;

FIG. 2 is a right side elevational view of the apparatus shown in FIG. 1;

FIG. 3 is a bottom plan view of the apparatus as shown in FIG. 1;

FIG. 4 is a rear elevational view of the apparatus shown in FIG. 1; and

FIG. 5 is a rear perspective view of another embodiment of a fluid delivery apparatus embodying my new design.

The clamp structure shown in the embodiment of FIG. 5 has been omitted from FIGS. 1-3 for ease of illustration.

This is a continuation-in-part of design application Ser. No. D. 20,774, filed Jan. 6, 1970 and now abandoned.

I claim:

The ornamental design for a fluid delivery apparatus, as shown and described.
